UNITED STATES PATENT OFFICE

2,110,447

TAPE PUNCHING DEVICE

Albert J. Levering, Haddon Heights, N. J.

Application July 3, 1936, Serial No. 88,708

7 Claims. (Cl. 164—112)

The invention relates to tape punching devices and more particularly to mechanism for punching or perforating a tape of the type used with automatic telegraphic transmitting systems.

5 It is an object of the invention to provide a tape punching or perforating device which will be simple in construction but reliable in operation.

10 It is a further object of the invention to provide improved mechanism for accurately advancing a message tape so that the same may be perforated.

15 It is a further object of the invention to provide a tape punching machine in which successive unit perforations in a tape may be combined in such a manner as to provide an improved multiple unit perforation.

20 It is also an object of the invention to provide a machine for punching tape which will be easy to operate and which will produce a properly perforated tape.

Other objects of the invention will appear from the specification and claims.

25 The nature and characteristic features of the invention will be more readily understood from the following description, taken in connection with the accompanying drawing forming part hereof, in which

30 Fig. 1 is a plan view illustrating a preferred embodiment of the present invention;

Fig. 2 is a vertical sectional view taken longitudinally, and approximately on the line 2—2 of Fig. 1;

35 Fig. 3 is a vertical sectional view taken laterally, and approximately on the line 3—3 of Fig. 2;

Fig. 4 is a vertical sectional view taken laterally, and approximately on the line 4—4 of Fig. 2;

40 Fig. 5 is a vertical sectional view taken longitudinally, and approximately on the line 5—5 of Fig. 1;

Fig. 6 is a plan view on a somewhat enlarged scale of the tape.

45 It will, of course, be understood that the description and drawing herein contained are illustrative merely, and that various modifications and changes may be made in the structure disclosed without departing from the spirit of the invention.

50 Referring more particularly to the drawing, the tape, designated as 10, has slots or perforations of different predetermined lengths punched therein as hereinafter pointed out. A slot of unit length is shown at 11, this being the unit ordinarily used for providing a punched "dot". A

longer slot is shown at 12, this being the length ordinarily used for providing a punched "dash". The length of the slot 12 is slightly less than three times the length of the unit slot 11. A still longer slot is shown at 13, the length thereof being 5 slightly less than five times the length of the unit slot 11.

Spaces between the slots are also provided, a space of unit length being shown at 14, and a longer space of a plurality of space units of 10 length at 15.

The length of the slots and the intervening spaces may be varied in substantially unit lengths with the device of the present invention but the lengths selected by the operator for the slots and 15 spaces will be uniform.

The apparatus comprising the present invention and for punching the tape 10, as referred to above, includes a frame or base portion 20 preferably of cast metal. 20

The frame 20 has centrally disposed at the rear thereof an upwardly extending standard 21 which is cast or otherwise secured to the horizontal portion of the frame 20. A tape drum or spool 22 is removably mounted on the upper end of the standard 21, preferably being journaled on a bearing pin 23 secured to the standard 21. A nut or other removable holding device 24 is provided on the outer end of the bearing pin 23 for holding the tape drum 22 in position on the bearing pin 23. 30

The frame 20 also has centrally disposed near the front thereof an upwardly extending guide standard 25. The guide standard 25 is provided with slotted portions 26 and 27, with stop pins 28 and 29 at the upper ends respectively of the slots 26 and 27. 35

The lower end of the standard 21 has a tape guide pin 30 mounted thereon for guiding and directing the tape 10 as it comes from the tape spool 22, and at the opposite end of the tape course, at the front of the frame 20, a tape bearing strip 31 is mounted. The tape bearing strip 31 is held on the frame 20 by a supporting pin 32. 40

Mechanism is provided for advancing the tape a predetermined distance. A space key member 35 is provided and includes a space key lever 36, with a finger portion 37 mounted at one end thereof. This end portion of the lever is reciprocal in the guide slot 27, upward movement of this portion of the lever 36 being limited by the pin 29 and downward movement being limited by the lower end of the guide slot 27. The other end of the space key lever 36 is pivotally mounted 45

50

55

on a bolt 38, which extends through the standard 21. A spring 39 coiled around the bolt 38 with one end bearing on the frame 20 and the other end hooked under the space key lever 36 normally urges the spacing lever 36 to its upper position, in contact with the stop pin 29.

A tape actuator shaft 40 is mounted in upwardly extending portions 41 and 42 of the frame 20. A tape driving roll 43, having a covering of suitable material such as soft rubber is mounted on the actuator shaft 40 directly above the tape bearing strip 31 in such a manner that the driving roll 43 will draw the tape 10 along the bearing strip 31 by frictional engagement of the roll 43 with the tape 10.

A toothed wheel 44 is also secured to the shaft 40 for engagement by a pawl 45. The pawl 45 is pivotally mounted on the spacing lever 36 by a rivet 46, and is held in engagement with the toothed periphery of the wheel 44 by a spring 47.

A punch key member 50 is provided and includes a punch key lever 51, with a finger portion 52 mounted at one end thereof. This end portion of the punch key lever 51 is reciprocable in the guide slot 26, upward movement of this portion of the lever being limited by the pin 28 and downward movement being limited by the lower end of the guide slot 26. The other end of the punch key lever 51 is pivotally mounted on the bolt 38 in the standard 21.

A punch spring 53 is provided and is mounted at one end upon a lug 54 formed on the frame 20, the other end portion of the spring 53 extending across the frame 20 with the extremity beyond the punch lever 51. Bolts 55 are preferably employed for holding the end portion of the spring 53 in engagement with the lug 54. A tape guide member 56 is mounted preferably by means of a bolt 57 on the frame 20 and beneath the spring 53. The other end portion of the tape guide member 56 extends beneath the extremity of the spring 53 and has a slot 58 formed therein.

A die member 60 in the form of a flat plate of spring steel metal is mounted on the frame 20 by suitable fastening means such as the bolts 61 and has an aperture 62 therein for reception of a tape punch member 63.

The tape punch member 63 is preferably rectangular at the lower end thereof, as at 64, the dimensions from front to back conforming to the unit length of the slot 11 and the dimensions from side to side conforming to the width of the slot 11. The punch member 63 is mounted on the punch spring 53, and has an upper end portion 55 thereof which passes through an aperture in the spring 53. A nut 65 on the upper end of the tape punch member 63 holds the same in position with respect to the spring 53.

The upper end of the tape punch member 63 is in contact with the lower edge of the tape punch lever 51 and is held in contact by the punch spring 53.

The operation of the device will now be pointed out.

65 The free end of the tape 10 on the tape drum 22 is introduced under the tape guide pin 30, then along the die member 60 and below the tape guide member 56 and then between the tape guide strip 31 and the drive wheel 43.

70 If the finger member 37 on the spacing lever 36 be pressed, the pawl 45 engages a tooth of the wheel 44 and further downward movement of the end of the lever 36 causes movement of the shaft 40 and of the drive wheel 43 carried thereby. The frictional contact of the drive wheel 43 on

the tape 10 forces the tape 10 toward the front of the device. In this manner, upon a single downward movement of the finger member 37, the tape 10 is advanced through one space unit. Upon completion of this advance of the tape 10, the spring 39 returns the spacing lever 36 to its initial position in contact with the stop member 29. Each repetition of this operation advances the tape 10 through one space unit.

When it is desired to punch a slot of unit 10 length, the finger member 52 of the punch lever 51 is pressed downwardly and the pressure exerted on the lever 51 is transmitted through the end portion of the punch member 63 against the force of the spring 53 and the punch member 63 is forced downwardly through the aperture 62 of the die 60. This removes a portion of the tape 10 in accordance with the form and shape of the punch and die members 63 and 60. The space key lever 36 is again operated and advances the tape 10 a single space unit for each actuation thereof. The tape is thus brought to a position for further punching or for the provision of a suitable number of spacing units. The operation of the space key lever 36 advances the tape 10 a 25 distance which is slightly less than the dimension from the front to the back of the portion 64 of the punch member 63 so that upon successive punchings a slight overlap of the punchings is effected. This insures a complete removal of 30 material from the tape in accordance with the length of slot desired.

I claim:

1. A machine for perforating tape including means for advancing the tape a predetermined unit distance for each actuation thereof, and means for punching in the tape a perforation of a length slightly in excess of the unit distance of advance.

2. A machine for perforating tape including a tape supply device, means for advancing the tape a predetermined unit distance for each actuation thereof, means for punching in the tape a perforation of a length slightly in excess of the unit distance of advance, said last named means including a die member, a punch member complementary to the die member and manually operable devices for actuating said punch member.

3. A machine for perforating tape including a tape supply device, means for advancing the tape a predetermined unit distance for each actuation thereof, means for punching in the tape a perforation of a length slightly in excess of the unit distance of advance, said last named means including a die member, a punch member complementary to the die member, tape guide means for holding the tape in position with respect to the die member, and manually operable devices for actuating said punch member.

4. In a machine for perforating tape, key operated mechanism for advancing the tape a predetermined distance for each actuation thereof, and independently actuatable key operated mechanism for perforating in said tape slots of predetermined length greater than the distance of 65 advance.

5. In a machine for perforating tape, key operated mechanism for advancing the tape a predetermined distance, and independently actuatable key operated mechanism for perforating in said tape slots of predetermined length greater than the distance of advance upon completion of the operation of the advancing mechanism.

6. A machine for perforating tape including a tape supply device, means for advancing said

tape from said supply device a unit distance for each actuation thereof, a punch for punching a slot of predetermined unit length in said tape, and manually actuatable punch control mechanism 5 separately operable with respect to the advancing mechanism for punching with the punch a slot of unit length upon a single operation thereof or for punching a continuous slot of multiple unit length upon actuation thereof, said mechanism 10 being operable between actuations of said advancing means.

7. A machine for perforating tape including a tape supply device, manually operable means for advancing the tape from the supply device a unit distance for each actuation thereof, and manually actuatable unit length slot punching 5 mechanism separately operable with respect to said advancing means for punching a slot in said tape of multiple unit length in punching operations between the respective actuations of said advancing means.

ALBERT J. LEVERING.
